UNITED STATES PATENT OFFICE.

VICTOR DEGERSTEDT, OF PORTLAND, OREGON.

HOIST.

1,182,757.

Specification of Letters Patent.

Patented May 9, 1916.

Application filed February 10, 1913. Serial No. 747,271.

To all whom it may concern:

Be it known that I, VICTOR DEGERSTEDT, a citizen of the United States, residing at Portland, in the county of Multnomah and State of Oregon, have invented certain new and useful Improvements in Hoists, of which the following is a specification.

My invention relates to hoists and has for its object, primarily, the utilization of a driving member that is constantly rotative in one direction for driving the hoist wherein two independent hoisting members or drums are made subject to the perfect control of an operator, so that they may be made, without interruption of movement of the driving members, to raise or lower a load at will, or to shift it to any desired position anywhere within predetermined limits.

20 A secondary object of my invention is to provide certain new and useful mechanism for the accomplishment of the primary object described.

What constitutes my invention will be hereinafter specified in detail and succinctly set forth in the appended claims.

In the accompanying drawings which constitute a part of this specification, Figure 1 is a plan view of my hoist with its ropes omitted. Fig. 2 is a diagrammatic side elevation of the same. Fig. 3 is a perspective view, partially diagrammatic, of the mast and booms which are employed, in practice, in the use of my hoist, and by the aid whereof the efficacy of said hoist is made available. In this figure are shown the flexible members or ropes of my hoist.

Referring to the numerals on the drawings, 2 indicates the base or frame of my machine. A driving member, rotative in one direction is conveniently carried on the frame 2 and is represented by the shaft 4. It is illustrated as driven by explosive engines 3. Such engines, as well as electric motors, are, from their nature, operatively limited in respect to the application under consideration, to a motion in one direction. It is in large measure, to meet this limitation in practice that my present invention is designed and adapted.

Omitting all further details of means employed, and well known in themselves for driving the shaft 4, save only a bare reference to a clutch 5, which is preferably provided, it may be specified that the shaft 4

is connected, as by a pair of gears 6 and 7, to a shaft 8 mounted on the frame 2 preferably in parallel relationship to the shaft 4. The shaft 8 may be regarded equally with the shaft 4 as the driving member of my 60 hoist since the only material distinction, is that the former is a step further removed from the power which drives them both.

Loosely mounted on a common shaft 24, to which is preferably fixed an intermediate 65 driving gear 10, common to both of them are two drums 11 and 12. The gear 10 derives motion from a pinion 9 on the shaft 8 and drives the drums independently of each other through coaction of any usual or preferred frictional or other clutch mechanism with which the opposing forces of the gear 10 and the drums, respectively, are provided.

Each drum is made operatively to engage 75 the gear by means of its movement lengthwise of the shaft 24. The details of the mechanism for operating the drums including that for shifting them longitudinally on the shaft 24 may be of any variety well 80 known in the art and do not, for that reason, require further description or more than the diagrammatic illustration given. Suffice it to say, in this connection, that the shifting motion of the respective drums with the effect above referred to of causing them to 85 rotate with the gear 10 is imparted by radial movement upon the drum shaft 24 of cranks 20, one of which is provided for each drum. Normally the drums run free of the gear 10 90 upon their shaft.

A shaft 17 is mounted upon the frame 2 parallel to the shaft 8. It carries toward its opposite extremities within the sides of the frame two loose sleeves 18, which are 95 connected as by respective links 19 with the cranks 20 one with one crank and the other with the other crank.

Each drum is provided with an independent brake represented by a brake-strap 23 100 bent about a bearing face on one flange of its drum and having its ends fastened to a lever 22 pivoted to a cross-rod 25 in the frame 2. The movement of each lever upon its pivot serves to apply or release its brake 105 strap to or from its drum. A link 21 operatively connects one lever 22 with a crank 26 mounted on the shaft 17 and a second link 21 connects in like manner a second crank 26, and the other lever 22. The cranks are 110

independently operable by separate pedals 16 loosely fixed upon the shaft 17 between the sleeves 18. Each of the sleeves 18 carries a crank 27 to which its respective connection with the links 19, above referred to, is made, and each sleeve has its separate hand-lever 15. By aid of the sleeves the collocation in close correlative assemblage of the two pedals 16 and of the two hand-levers 15 is made possible, whereby an operator seated upon a support or seat 13, properly disposed upon a bracket 14 projecting from the frame 2, is enabled to maintain under all conditions in service such complete operative control of the machine as will be hereinafter more fully explained in the description of the operation thereof.

In Fig. 3 the flexible members or ropes 39 and 43, which it is the function of the drums 11 and 12, respectively to wind and unwind, but which, for clearness, are omitted from the preceding figures, are shown. The desired operation of the machine depends upon the relative disposition of its ropes with respect to the load to which they are attached and which may be attained as through the employment of a mast and boom arrangement, which although, in itself, of familiar use in connection with hoisting machinery, it is deemed to be conducive to clearness in this specification to illustrate and describe.

Proceeding accordingly, 31, in Fig. 3, indicates a mast which is planted upon any suitable floor or deck 32. It carries near its foot a collar 33, adjustable as required, which supports the lower ends of a pair of booms 34 and 35. The booms may be adjusted to any desired angle of inclination 40 toward the mast as by halyards 36. Guys 37 serve to retain the booms at a desired limit of expansion from each other that is fixed as by an intermediate or stretcher rope 38.

Upon such a boom construction as the one described, a rope 39, is led by pulleys 40 and 41 from the drum 11 to a load engaging member or hook 42, to which also a rope 43 is led by pulleys 44 and 45 from the drum 12. The load 46 upon the hook 42 depends from the two ropes 39 and 43 that are united by the hook.

From the foregoing it will be apparent to one skilled in the art in considering the operation of my machine, that if the ropes 39 and 43 be arranged to wind upon their respective drums when under driving control, they will unwind under the action of the gravity of the load 46, either conjointly or 60 separately, whenever both or either of the drums is released from its driving gear 10.

A third factor in determining the relative action of the ropes upon the load is introduced by the employment of a brake for 65 each drum, whereby not only may the move-

ment of both drums be interrupted, at will, upon the disengagement of both from the gear 10, but also one drum may be held stationary while the other is being driven in one direction or the other, either by the action of gravity, through the weight of the load, or by that of the gear 10.

It will now be evident that by the use of my machine the load may be lifted from any point at which it may be reached by the hook 42, and may then be, through the resultant of forces, operating upon it, deposited with practical precision to any desired position located between verticals let fall from the pulleys 41 and 45. Furthermore it being now obvious that the various forces that are utilized in the operation of my machine are controlled exclusively by means of the two hand levers 15 and the two pedals 16, it must also be apparent that each of the four members last named must be under instant control while the machine is in operation, under penalty of incurring damage to the machine or to its load. That necessary control indicated in the last sentence, may not be had unless each of said four members be kept constantly under the hand or foot of the operator that is appropriated to it, no shifting of the hands or feet being practicable in the operative control of the machine. In order that both hands and both feet may be so appropriated and each ready for instant service, the seat 13 becomes not a member of convenience, but one of necessity, without which the machine is impracticable and useless for performing those functions for which it is designed.

The collocation of the hand levers 15 and pedals 16 in close assemblage within operative proximity to the operator or in other words, to the seat 13, is for like reason equally essential.

It may not be improper to add, not only, that skill in the operation of the machine requires the operator to observe constantly the hang of the load 46 so as to keep its weight duly distributed upon both ropes 39 and 43, but also that, by reason of my invention, such expertness is readily attainable by a competent man.

What I claim is:

1. In a hoist comprising a frame, a driving shaft, a pair of drums, means for engaging and disengaging, at will, said shaft and drums, and means for braking and releasing either or both of said drums when disengaged from said shaft, the combination with a shaft carried by said frame, of four movable members respectively connected with said respective means and demanding exclusive appropriation of both hands and feet of the operator at the same time, said members being carried upon said shaft in close correlative assemblage with one another whereby they may be operated

independently at the same time by the hands and feet of a single operator, substantially as and for the purpose specified.

2. In a hoist comprising a frame, a driving shaft, a pair of drums, means for engaging and disengaging, at will, said shaft and drums, and means for braking and releasing either or both of said drums when disengaged from said shaft, the combination with a shaft carried by said frame, of pedals movably incorporated upon said shaft with said means for braking and releasing, sleeves also movable upon said

shaft and operatively incorporated with said engaging and disengaging means, and hand levers upon said sleeves, respectively, said 15 pedals and hand levers being collocated in close correlative assemblage to an operator's support provided upon said frame and operable in parallel planes.

In testimony whereof I hereunto affix my signature in the presence of two witnesses.

VICTOR DEGERSTEDT.
